UNITED STATES PATENT OFFICE.

LEWIS GIBBS, OF CANTON, OHIO, ASSIGNOR TO BUCHER, GIBBS & CO., OF SAME PLACE.

SULKY-PLOW.

SPECIFICATION forming part of Letters Patent No. 329,731, dated November 3, 1885.

Application filed June 9, 1885. Serial No. 168,199. (No model.)

To all whom it may concern:

Be it known that I, LEWIS GIBBS, a citizen of the United States, and a resident of Canton, county of Stark, State of Ohio, have invented 5 a new and useful Improvement in Sulky-Plows, of which the following is a full, clear, and exact description, reference being had to the accompanying drawings, making part of this specification.

10 My invention relates to an improvement in sulky-plows.

The object of my invention is to provide in a sulky-plow such construction of parts and arrangement by which the operator may have 15 control of the plow during its progressive movement. A further object consists in such adaptation and location of a seat for the operator that his weight may be utilized in raising or otherwise controlling the plow. A further object consists in a rectangular main 20 frame-section provided with spindle-bearing quadrants that vibrate about a center and are adapted for adjustment with the frame. A further object is to provide a center or pivotal 25 point about which a spindle-bearing quadrant may be vibrated that can be adjusted during the progressive movement of the plow. A further object is to provide a toothed sector integral with a flanged corner-support for the 30 main frame and a hand-lock lever and link-connection with a sliding spindle-bearing quadrant. A further object is to provide a base or support for a hand-locking lever that is integral with a flanged corner-support for 35 the main frame. A further object consists in the combination of the tongue-frame section hinged to the main frame, and adapted at its front end for engagement with a tongue, which in turn is adapted for such engagement, and 40 provided with means for lateral adjustment. A further object consists in providing an adjustable foot-lever, pivoted to the tongue-frame section and extending through a bell-crank and link to a standard, which in turn is adjustable with a plate attached to the plow-beam.

With these objects in view my invention consists in certain features of construction and combination of parts hereinafter described, 45 and pointed out in the claims.

In the accompanying drawings, Figure 1 is a rear view in elevation of my improved sulky-plow, in which are shown the several parts in their respective places when the plow is operated. Fig. 2 is an enlarged perspective of the spindle-bearing quadrant and a section of the main frame, showing the relation of the spindle to the quadrant and the manner of connection with the frame. Fig. 3 is a side elevation with wheel removed and the rear 55 end of side brace of tongue-frame removed, so as to show more clearly the parts as they will be referred to and explained herein. Fig. 4 is a view showing the connection of the tongue with tongue-frame and the means of adjustment. Fig. 5 is a view of the foot-lever connection with the bell-crank. Fig. 6 is a perspective of the beam-clamping plate and adjustable standard. Fig. 7 is an enlarged view 60 in perspective of a detached portion of the 70 main frame with corner-iron and lock-lever attached, and a portion of the tongue-frame with toothed sector attached. Fig. 8 is a similar view of the opposite corner of the main frame, in which is shown the corner-iron, the 75 connection with the tongue-frame, the toothed sector, the hand lock-lever, and link-connection with the spindle-bearing adjustable quadrant.

The frame is made, preferably, of two flat 80 metal bars, A, bent in the form shown in Fig. 1, with the ends abutted together at a and bolted to the hinge F, hereinafter described, and a round bar, A', joined to the ends of the respective bars A. The clamps B' and B'', 85 that secure the parts A and A', are made in halves and have round seats d at one end for embracing the bar A' and flat seats d' at the other end for grasping the flat bars. The spindle-bearing quadrant B may be bolted to 90 the frame-bar A, as shown in Fig. 2. The bolt e, the pivotal point around which the plate B, with the wheel-spindle C attached, may be vibrated for the purpose of adjustment, and the bolt e' may be passed through 95 one of the holes in the arc of the plate and the frame to secure it in the desired position. This adjustment may be made at different points on the frame-bar A by moving the plate on the bar and securing it by the same 100

means and in the same manner, holes being provided in the bar for that purpose. This adjustment can only be made when the plow is at rest. The wheel-spindle C may be made 5 integral with the quadrant-plate or separate, and placed at any desired point on the plate between the pivot and the periphery. By vibrating the plate and spindle about the pivotal point any adjustment of the wheel 10 may be had that is required. The spindle-bearing quadrant D is mounted on a sliding plate, E, having longitudinal side ribs that embrace the frame-bar A, and the ears $e^1 e^2 e^3$ 15 to which the quadrant is attached by the through bolts $f^1 f^2 f^3 f^4$, as shown in Fig. 8. The quadrant-plate is provided with a pivotal point at the upper rear corner, a circular or segmental slot in the rear lower corner, and two rows of holes, each on a line of different 20 diameter from the pivotal point. By removing the bolts f^2 and f^3 from the hole and slackening the bolt f^1 the quadrant-plate and spindle may be vibrated about the pivotal bolt f^4 and secured at the desired position of adjustment 25 by inserting the bolts f^2 and f^3 . The wheels G are mounted on the spindles C and secured by the nuts g g. The corner-support H of the main frame is provided with flanges m, that embrace the frame, and is secured there- 30 to by through-bolts, and is further provided with ears l, that extend forward as a hinge-support for the tongue-frame K, and is further provided with a toothed sector, L, and a support for a hand-lock lever, M. These parts 35 are of metal and preferably integral. The hand-lever M is pivoted to the sector in a suitable manner, and a spring-dog, h, engages the notches on the sector, and is operated by the lever h' , of the bell-crank variety, and 40 connected with the dog by the rod i. From the hand-lever M there extends a link, J, which is connected to the sliding plate E by the bolt k, as shown in Fig. 8. Corner iron or support N is provided with flanges to 45 embrace the frame, lugs or ears l extending forward as a hinge and support for the tongue-frame K, and a hand-lever, P, formed integral and preferably of malleable iron. A toothed sector, O, is bolted to the tongue-frame K and hinged to the corner-piece N. The hand-lever P is provided with a spring-dog, r, connected by the rod s to the bell-crank handle t, thus forming a locking mechanism by which the tongue-section and the 50 main-frame section may be locked and held in any desired position.

The hinged tongue-frame section is composed of the following parts: a center-piece, S, mounted with a suitable hinge-piece, F', by 55 which it is connected to a corresponding hinge-piece, F, bolted to the front bar of the main frame and the lap-plate a. Braces K extend from a point near the front end of this center piece at an angle of about forty-five degrees 60 to the hinges R, provided on the corners of the main frame. The tongue T may be attached to the tongue-frame by the adjustable

clamping-plates U and V, rigidly attached to the tongue by the bolts 1 and 2, and pivoted on bolt 3 and adjusted on bolt 4 by the engagement of the notches with the bolt-head, which is adapted for such engagement, the object of which will be hereinafter explained. The spring for the operator's seat is attached to the center-piece of the tongue-frame, and 70 so located as to bring the seat in front of spindles of the supporting-wheel, that the weight of the operator may be utilized as a balance in raising the plow.

To adapt the main frame to a high or low 80 beam plow, the spindle-bearing quadrants may be vibrated about their pivotal points and adjusted as may be desired.

The plow may be attached to the main frame in the following manner: Plate B³ has 85 upwardly-projecting angular ribs, and similar ribs depend from plate B⁴. When these plates are in position, the respective ribs register, and between the opposing central and angular parts of the ribs there is room for the bar A'. The plow-beam X is placed above the plate B³, between it and the clamping-plate W, and secured by bolts extending up through the plates B³ and B⁴ on either side of the beam and through the clamping-plate W, that 90 rests on the top of the beams, and are provided with nuts, by means of which the parts are securely fastened. The collars e and n on the bar A' are provided with set-screws, and may be used to adapt the plates to either a right 95 or left hand plow. With this construction, the plates may swing in either direction, as on a pivotal point, so that the plow may assume any position required in turning corners and avoiding obstructions. The foot-lever R' 100 is provided at one of its ends with a suitable rest for the foot. The other end is adapted for adjustment with a bell-crank, S', which is pivoted to the tongue-frame, and provided with a serrated disk, D', to which the foot-lever may 105 be adjusted and secured by the through-bolt M'. The upper end of the bell-crank S' is connected by a link, T', to the upper end of the arm U', the lower end of which is provided with a serrated disk, which is adapted 110 for engagement with a similar disk on the beam-plate W, and may be held in such adjustment by the through-bolt w. When in 115 operation, the main frame will project from the tongue-frame on an angle of about thirty 120 degrees. By a depression of the foot-lever the plow may be made to more readily enter hard ground; or to release the plow from obstructions a downward movement of the lever through its connections will cause the plow to 125 move backward as well as upward. To further elevate the plow, release the lock-lever P from the toothed sector, and the weight of the operator will raise the plow until the main frame has reached a line about parallel with 130 the tongue-frame.

To regulate and adapt the plow to the ground and conditions that may be met during its progressive movement, the lever M may be moved

forward or back, and through its connection with the sliding plate E will move the wheel-spindle on the main frame and secure the desired adjustment. For further adaptation the tongue may be moved at its point of connection with the tongue-frame and adjusted therewith.

Having thus fully described the nature and object of my invention, what I claim, and desire to secure by Letters Patent, is—

1. In a sulky-plow, a spindle-bearing quadrant adapted to vibrate about a pivotal point mounted on a sliding plate and for adjustment thereto, as described, and for the purpose set forth.

2. In a sulky-plow, the combination of the adjustable spindle-bearing quadrant, the sliding plate, and the connecting-link with the locking hand-lever, as described, and for the purpose set forth.

3. In a sulky-plow, the combination of a sliding spindle-bearer that embraces the side piece of the main frame, a connecting-link, and a locking hand-lever, as shown and described, and for the purpose set forth.

4. In a sulky-plow, a corner-support, H, to the main frame A, provided with flanges to embrace and support the frame and ears as a hinged support for the tongue-frame, and a toothed sector integral and adapted to support and engage with the locking hand-lever, as shown and described, and for the purpose set forth.

5. In a sulky-plow, a corner-support, N, to

the main frame, provided with flanges to embrace and support the main frame and ears as a hinge-support for the tongue-frame, and a hand locking-lever integral therewith, and adapted for engagement with a toothed sector, as shown and described, and for the purpose set forth.

6. In a sulky-plow, the combination of the foot-lever R', bell-crank S', connecting-link T', adjustable arm U', and plate W, as shown and described, and for the purpose set forth.

7. In a sulky-plow, a spindle-bearing quadrant or plate adapted to vibrate about a center and for adjustment and engagement with the side piece of the main frame, in combination with the locking hand-lever P, as described, by which the frame may be rocked forward and over the spindle, as described and set forth.

8. In a sulky-plow, the combination, with a plow-frame, wheels secured thereto, the corner irons or supports N, the tongue-frame hinged to said corner-irons, and a hand-lever formed integral with said corner-irons, of the sector O, rigidly secured to the tongue-frame and loosely secured to the ears l of the corner-irons, substantially as set forth.

In testimony whereof I have hereunto set my hand this 30th day of May, A. D. 1885.

LEWIS GIBBS.
